UNITED STATES PATENT OFFICE.

OSWALD L. W. DIETZ AND FRED HAAF, OF CINCINNATI, OHIO.

CAR-COUPING.

SPECIFICATION forming part of Letters Patent No. 437,582, dated September 30, 1890.

Application filed June 11, 1890. Serial No. 355,104. (No model.)

To all whom it may concern:

Be it known that we, OSWALD L. W. DIETZ and FRED HAAF, citizens of the United States, and residents of Cincinnati, in the county of 5 Hamilton and State of Ohio, have invented certain new and useful Improvements in Automatic Car-Couplings; and we do declare the following to be a full, clear, and exact description of the invention, such as will enable 10 others skilled in the art to which it appertains to make and use the same, reference being had to the accompanying drawings, and to letters of reference marked thereon, which form a part of this specification.

15 Figure 1 of the drawings is a side view. Fig. 2 is a top plan view. Fig. 3 is a vertical transverse section, and Fig. 4 is a detail view.

This invention relates to certain improvements in car-couplings; and it consists in the 20 construction and combination of parts, as will appear hereinafter.

In the drawings, A refers to the draw-bar, which has a sliding connection with the draft-rod a by means of a cross-bar a', projecting 25 from the latter through slots a² in inner extension of said draw-bar to provide for a limited endwise play of the draw-bar.

B is the coupling-hook, preferably flared from its ends toward the middle and having 30 at said ends beaks or projections b, which drop into or engage cavities c—one in the bottom of each of two draw-bars A. The bottom of the hook-receiving chamber d of the draw-bar has a double inclination sloping from its 35 center inward and outward, the outward slope adapting said chamber to receive coupling hooks or links from draw-bars of different heights. The elevation thus formed at the meeting ends of the inclines of the double 40 inclination provides for the required oscillation of the coupling hook or link.

C C' are clamps or jaws engaging the coupling-hook B and preventing the accidental disengagement of the beaks or projections of 45 said hook from their receiving-cavities and arranged one somewhat in advance of the other in openings d' d² in the side walls of the hook-receiving chamber of the draw-bar.

The outer portions of the jaws or clamps C 50 C' are encircled by and to them are connected springs D, held or contained in hollow screw-

plugs e, screwed into the draw-bar to automatically hold said jaws or clamps in engagement with the coupling-hook and to likewise return them to their normal position when 55 their engaging ends are relieved of pressure. The opening d', receiving the jaws or clamps C', has a greater vertical depth than the jaw or clamp in order to permit its vertical adjustment to provide for its adaptation to the 60 height of the incoming coupling-hook. This adjustment of the clamp or jaw C' is effected by means of a screw-threaded or adjusting hanger or bolt F, engaging a screw-threaded vertical opening in the draw-bar A and hav- 65 ing a neck f, passing through a slot f' in said jaw or clamp and having a shoulder f² on its lower end engaging an enlargement of said slot.

G is a cam centrally pivoted in an opening 70 g in the draw-bar A and below the coupling-hook and having the oppositely-curved portions of its horns or points engaging anti-frictional rollers h, journaled or arranged upon rods H, passing through said opening 75 and vertical slots i in alignment therewith and the jaws or clamp openings. Said rods H connect with the jaws or clamps C C' and are guided at their lower ends in grooves j in a casting or plate I, bolted to the under side of 80 the draw-bar A.

The cam G has on its upper side or surface a spiral or cam shoulder k, engaging a pin or slide l, arranged in an opening l' in the bottom of the coupling-hook chamber directly 85 under the coupling-hook, and the said cam has connected to it at its extremities handled levers J, reaching outward so as to be conveniently manipulated without passing between the cars. Thus it will be seen that by 90 moving either one of the handled levers J the cam G is actuated so as to disengage through the rods H the clamps or jaws C C' from the coupling-hook, and said coupling-hook is simultaneously lifted out of the cavity receiving the beak or projection on that end of the hook, thereby effecting the uncoupling of the cars.

The coupling operation is, as will have been observed from the preceding description, automatically effected.

Having described this invention, what we

claim, and desire to secure by Letters Patent, is—

1. The car-coupling having the spring-pressed jaws or clamps arranged in the coupling-hook or link-receiving chamber, one of said jaws or clamps being vertically adjustable, said chamber also having a cavity or recess to receive the beak or projection of said hook, substantially as set forth.
2. The car-coupling having the spring-pressed jaws or clamps adapted to engage the coupling-hook or link whose beaks or ends engage cavities in the draw-bar, and a cam engaging a pin or slide engaging said hook, substantially as set forth.
3. The car-coupling having a cam provided with a spiral or cam-shoulder engaging a sliding pin engaging the coupling-link and the handled lever for manipulating said cam, substantially as set forth.
4. The car-coupling having the cam provided with the actuating-levers and a spiral shoulder engaging a sliding pin engaging the coupling-hook and the rods connected to the

clamp or jaws and adapted to be actuated by said cam, substantially as set forth.

5. The car-coupling having the coupling-hook engaging clamps or jaws arranged in the draw-bar, one being adjustable by means of a screw having a neck passing through a slot in said jaw, and a shoulder on said neck engaging an enlargement of said slot, substantially as set forth.

6. The car-coupling having the coupling-hook engaging jaws or clamps and the cam engaging rods connected to said jaws or clamps and having their lower ends guided in grooves in a plate or casting on the under side of the draw-bar, together with means for actuating said cam, substantially as specified.

In testimony whereof we affix our signatures in presence of two witnesses.

OSWALD L. W. DIETZ.
FRED HAAF.
